UNITED STATES PATENT OFFICE.

JACOB KAUTZ, OF CHICAGO, ILLINOIS.

SELF-ADJUSTING DOORLOCK.

Application filed August 16, 1924. Serial No. 732,553.

This invention relates to new and useful improvements in door locks and more particularly to that type known as the sliding latch lock. The main object of my invention is the provision of a lock of the sliding bolt type wherein the bolt is formed to provide for transverse movement of the same as well as longitudinal movement whereby the same may ride upon an inclined surface on the locking plate and be positioned within the usual opening formed in the locking plate behind a shoulder which is beneath the inclined portion so as to positively prevent the bolt from becoming disengaged from the locking plate unless manually manipulated.

Another object of my invention is the provision of a sliding latch lock wherein the opening through the face of the lock is so arranged and the latch bolt so constructed as to permit the face plate to be interchanging without interfering with the operation of the latch bolt.

With the above and other objects in view, the invention consists in the novel features of construction, the combination and arrangement of parts hereinafter more fully set forth, pointed out in the claims and shown in the accompanying drawings, in which:

Fig. 1 is a detail elevation of a door having my improved lock applied thereto,

Fig. 2 is a front elevation of the lock,

Fig. 3 is a detail section on the line 3—3 of Fig. 2,

Fig. 4 is a front elevation of a lock plate applied to the door jam,

Fig. 5 is a detail transverse section on the line 5—5 of Fig. 4,

Fig. 6 is a detail elevation illustrating a slightly modified form of latching bolt.

In carrying out my invention the usual body member 1 of a lock is provided and which includes the sliding latch member 2 with the diverging arms 3 arranged upon opposite sides of the actuating spindle 4 to which the usual knobs are attached. The construction illustrated includes the lugs 5 attached to the bolt 4 and engaging outward ends 6 of the latch member 2. The forward edge of the body 1 is manually opened but in the present instance is closed by a detachable face plate 7 which is attached to the ears 8 on the body 1 by means of the screws 9. Arranged within the body 1 adjacent the upper face thereof is a guide

block 10 and an opening 11 therethrough through which the head 12 of the latch member operates, the same being thrown forwardly to a retaining position by means of a spring member 13 arranged within the body 1.

The plate 7 is provided with the usual lock bolt opening 14 and in the present instance the opening 15 through which the latch operates is disposed at an oblique angle with respect to the position of the plate 7 as clearly illustrated in Fig. 2 and this opening is longer than the length of the latch head 12 to permit movement of the latch head in the opening 15 so that the same may raise and lower as set forth hereinafter.

The latch head 12 has bevelled portions 16 and 17, the bevelled portions 17 corresponding with the inclined side walls of the opening 15 whereby to properly guide the latch head 12 in its movement lengthwise of the opening. A latch head 12 is likewise provided with bevelled surface portions 16' and 17' corresponding with the inclined side walls of the opening 19.

The strike locking plate 18 which is attached to the door jam is provided with a latch receiving opening 19 disposed at an oblique angle with respect to the plate 18 and this opening is preferably extended at an angle opposite the opening 15 in the plate 7 whereby when the patch head 12 is arranged in a retaining position within the opening 19 of one of the bevelled portions 16' will engage the forward wall of the opening 19 or that portion of the wall which forms a stop for the latch. In Fig. 4 it will be noted that the plate 18 is provided with an extension 20 having a shallow recess 21. From this construction it will be apparent that when the door is closed the tapering face of the latch head 12 will engage within the recess 21, the lower edge of the latch head riding upwardly upon the incline 22 until the latch head is forced into the opening 19 through the tension of the spring 13. One of the bevelled portions 16' on the latch head will then engage the wall of the opening 19 which forms a stop shoulder beneath the inner end of the bevelled portion 22.

As will be evident from the description herein the latch bolt is adapted for engagement with the inclined surface 22 and upon engagement therewith is adapted to ride

upwardly thereupon to a point where the latch bolt head is disposed in the opening 19, by the action of the spring member 13, with the bevelled surfaces 16' and 17' thereof, engaging the adjacent inclined side walls of this opening. As the opening 19 is disposed at an oblique angle with respect to the opening 15 it is manifest that when the latch bolt head is in engagement in the opening 19, as above stated, any vibration of the door, on its hinges, will cause the latch bolt head to settle downwardly in its engaged position in the openings 15 and 19 and be wedged therein thus preventing self-displacement of the latch bolt head from engaged position, thereby accomplishing one of the many objects of the invention.

In Fig. 6 I have illustrated a slightly modified form of latch member wherein the stem of the latch member is provided with an enlarged portion 23 having inclined opposed faces 24 which are engaged by the pin 25 carried by the casing of the lock for raising the latch head 12 upon its closing movement thus permitting the latch head to be sprung into the opening 19 of the locking plate 18 and thence dropped downwardly into a secure latching position.

It will be apparent that the plate 17 may be readily reversed and the latch member operated in the same manner as set forth above.

While I have shown and described the preferred embodiment of my invention, it will be understood that various changes and alterations may be made without departing from the spirit of the invention or the scope of the appended claims.

Having thus described my invention, what I claim is:

1. A lock member including a spring pressed latch bolt, a lock body, a detachable plate upon one side of the body having an opening therethrough disposed at an oblique angle with respect to the plate, a head on the latch bolt, bevelled surfaces on the head for engaging the walls of the inclined opening and means whereby to actuate said latching bolt as for the purposes set forth.
2. A lock member including a spring pressed latching bolt, a lock body, a detachable plate upon one side of the body having an opening therethrough disposed at an oblique angle with respect to the plate, a head on the latch bolt, and means for moving said latching bolt in a substantially vertical plane during the longitudinal movement of said latch bolt.

3. In combination with a locking plate 60 having an opening disposed at an oblique angle to the plate, an extension on the plate adjacent the opening having a transverse recess with one wall disposed upon an incline, of a lock member having detachable 65 face plate with an opening disposed at an angle relative to the plate and adapted for transverse movement whereby when the same is engaged with the locking plate it will ride upwardly upon the incline wall 70 and drop into the opening in the locking plate for engagement behind a portion of the plate adjacent the incline wall.

4. The combination with a strike plate of a door jam having an opening formed 75 therein extending at an oblique angle with respect thereto, of a face plate having an opening formed therein and extending at an oblique angle with respect thereto and at an opposite angle with respect to the opening of the strike plate, and a latch bolt having beveled longitudinal sides adapted for engagement in the opening of the strike plate and the opening of the face plate.

5. The combination with a strike plate of a 85 door jam having an opening formed therein extending at an oblique angle with respect thereto and having an inclined surface portion leading up to said opening, of a face plate having an opening formed therein and 90 extending at an oblique angle with respect thereto and at an opposite angle with respect to the opening of the strike plate, and a latch bolt adapted for engagement with the inclined surface portion adapted to ride 95 thereupon up to and into engagement with the opening of the strike plate and the opening of the face plate.

6. The combination with a strike plate of a door jam having an opening formed there- 100 in extending at an oblique angle with respect thereto and having an inclined surface portion leading up to said opening, of a face plate having an opening formed therein and extending at an oblique angle with respect 105 thereto and at an opposite angle with respect to the opening of the strike plate, and a latch bolt adapted for engagement with the inclined surface portion adapted to ride there- upon up to and into engagement with the 110 opening of the strike plate and the opening of the face plate, said latch bolt being pro- vided with bevelled surfaces for engagement with adjacent wall portions defining the first mentioned opening and the second men- 115 tioned opening.

In testimony whereof I affix my signature.
JACOB KAUTZ.
